UNITED STATES PATENT OFFICE.

EDWARD FITZ-GERALD LAW, OF RENO, NEVADA, ASSIGNOR TO UNITED STATES ENGINEERING COMPANY, A CORPORATION OF NEVADA.

ROLLER MILL.

Application filed October 12, 1926. Serial No. 141,191.

This invention relates to improvements in quartz mills and particularly to improvements in the quartz mill illustrated in the patent to Edwin G. Trowbridge, granted on

5 July 15, 1924, No. 1,501,503.

The general object of the invention is to provide a quartz mill comprising two opposed heads and circumferentially extending liner bars operatively mounted upon the heads so as to form a drum or barrel, these liner bars being separated from each other by shims so as to permit the quartz powdered by the balls disposed within the tumbling mill to be discharged.

10 A further object is to provide improved means for supporting these circumferentially extending liner bars and holding these arcuate bars or liners in place, yet permitting these liners or bars to be adjusted into 20 spaced relation to each other by the use of shims.

Other objects will appear in the course of the following description.

My invention is illustrated in the accompanying drawings wherein:—

Figure 1 is a front elevation of a quartz mill constructed in accordance with my invention;

Fig. 2 is a vertical transverse sectional view therethrough;

Fig. 3 is a section on the line 3—3 of Figure 2;

Fig. 4 is an end elevation of the machine;

Fig. 5 is a section on the line 5—5 of Figure 4.

Referring to these drawings it will be seen that this roller mill or tumbling mill is formed of two spaced heads designated 10 and 11, the head 10 being provided with an end plate 12, carrying a tubular shaft or trunnion 13 mounted in suitable bearings 14, this tubular shaft acting as means whereby quartz or other material may be fed into the interior of the rotating barrel. The opposite head is provided with means for supporting any suitable gear wheel or other means whereby the barrel may be rotated by power. The margin of each head is provided with a plurality of evenly spaced outwardly protuberant lugs 16, perforated for the passage of bolts and inward of the periphery of the head, each head is formed with a series of

outwardly protuberant portions 17 and intermediate recesses 18. Certain of these recesses 18 are disposed in line with the edges 55 of the lugs 16 and a recess is preferably disposed midway between the lugs 16.

Extending transversely across between the heads are a plurality of bracket bars designated generally 19, each of these bracket bars being for the greater portion of its length, rectangular in cross section and provided with the flanges 20, these flanges extending laterally from the bracket bars or circumferentially with reference to the drum. 65 Each bracket bar at its extremities is formed with the stud bolts 21 which are screw-threaded for the reception of nuts 22. These stud bolts are adapted to be inserted through apertures in the lugs 16 and the heads held against the shoulders 23 by the nuts 22. I have shown eight of these bracket bars extending transversely across the drum or barrel but I do not wish to be limited to this number as fewer bracket bars 75 might be used if desired.

Disposed between and resting upon these bracket bars are the arcuate or curved, circumferentially extending liner bars 24 which are preferably formed of manganese steel. 80 Each of these liner bars at its extremities is cut away to provide a tongue or lug 25 which rests upon the upper face of the adjacent flange 20 and supports the liner bars with their inner faces approximately flush 85 with the inner faces of the bracket bars. The liner bars are, under ordinary circumstances, about $1\frac{1}{4}$ " wide and, therefore, a plurality of these liner bars will be disposed side by side between each pair of bracket or 90 supporting bars 19, and the space between these liner bars permits the discharge of finely powdered quartz or other material.

For the purpose of holding the liner bars in place against the flanges of the bracket bars, I provide a plurality of transversely extending radially disposed backing bars 26 which are rounded upon their inner faces and bear against the liner bars and are held in place by bolts 27 passing radially through the backing bars, through the flanges of the heads, and into recesses 18. The head of the bolt 27 is disposed within the corresponding recess 18 and the outer end of the bolt is

engaged by a nut 28 which forces the backing bar inward against the liner bars, thus holding these liner bars rigidly in place. These backing bars are preferably made of 5 mild steel.

Disposed within the barrel formed by the liner bars are one or more rolls 29 having a length nearly equal to the length of the barrel and slightly rounded at the ends, but 10 which may be of any suitable construction.

The operation of a tumbling mill of this character needs no description but in the operation of this mechanism the quartz rock is fed into the interior of the barrel through 15 the feed opening formed in the tubular bearing or journal and the crushed quartz is discharged through the spaces between the liner bars. Preferably the quartz is carried into the interior of the barrel by a current of 20 water and the grinding is thus done with water. The liner bars are spaced from each other varying distances, depending upon the circumstances of operation, by means of shims 30 inserted between the liner bars at 25 the ends thereof and forcing these liner bars laterally apart. For this purpose I may use either ordinary shims or such as those disclosed in the said patent to Edwin G. Trowbridge, heretofore referred to. The shims 30 are placed at the points of contact with the backing bars. When these shims are introduced between the liners, the nuts on the extremities of the bracket bars are loosened to permit the lateral movement of the liner 35 bars due to the introduction of the shims, and then these nuts are tightened up again and thus the liners are drawn tightly together against the shims. Thus, any desired "mesh" may be secured by introducing the 40 proper shims between the liners.

It will be seen that in a tumbling mill or roller mill constructed in accordance with my invention there is much less impediment to the proper movement of the rollers than 45 where the liner bars run transversely or parallel to the axis of the barrel as in the Trowbridge patent, heretofore referred to. In the Trowbridge construction a plurality of facets are formed by the liner bars and 50 thus the smooth rolling movement of the rollers is impeded and a uniform grinding or crushing of the rock is prevented. With my improved mill the liners are never shifted radially outward or radially inward by 55 the introduction of shims as they must be in the construction of Trowbridge, but the liners have a uniformly curved inner surface flush with the bracket bars so that the rollers have a uniformly curved surface over which to roll and thus secure a maximum crushing 60 action which will produce powder of uniform fineness.

I claim:—

1. A roller mill including opposed heads, 65 transversely extending bracket bars mount-

ed between said heads and having flanges, and arcuate liner bars extending circumferentially of the barrel and having their ends resting upon and supported by said flanges, and having their inner faces flush with the 70 inner faces of the bracket bars, there being a plurality of liner bars disposed side by side between the heads, the liner bars being adapted to be spaced from each other by means of shims inserted between the liner 75 bars.

2. A roller mill of the character described including opposed heads, transversely extending bracket bars disposed between said heads, the ends of the bracket bars having 80 screw-threaded portions passing through the heads, nuts engaging said screw-threaded portions and holding the heads in spaced relation upon the bracket bars, each of said bracket bars being longitudinally flanged, a 85 plurality of arcuate liner bars disposed between each pair of bracket bars and cut away to rest upon the flanges of the bracket bars and having their inner faces flush with the inner faces of the bracket bars, and 90 means for holding said liner bars in place against outward movement.

3. A roller mill of the character described including opposed heads, transversely extending bracket bars disposed between said 95 heads, the ends of the bracket bars having screw-threaded portions passing through the heads, nuts engaging said screw-threaded portions and holding the heads in spaced 100 relation upon the bracket bars, each of said bracket bars being longitudinally flanged, a plurality of arcuate liner bars disposed between each pair of bracket bars and cut away to rest upon the flanges of the bracket bars and having their inner faces flush with 105 the inner faces of the bracket bars, and means for holding said liner bars in place against outward movement, comprising transversely extending backing bars operatively connected at their ends with said 110 heads and bearing against the outer faces of the liner bars.

4. A roller mill of the character described including opposed heads, transversely extending bracket bars disposed between said 115 heads, the ends of the bracket bars having screw-threaded portions passing through the heads, nuts engaging said screw-threaded portions and holding the heads in spaced relation upon the bracket bars, each of said bracket bars being longitudinally flanged, a 120 plurality of arcuate liner bars disposed between each pair of bracket bars and cut away to rest upon the flanges of the bracket bars and having their inner faces flush with the inner faces of the bracket bars, and means for holding said liner bars in place against outward movement, comprising transversely extending backing bars resting 125 at their ends upon the peripheries of 130

the heads and bearing against the outer faces of the liner bars, and bolts passing through the ends of each bracket bar and radially through the heads, the heads being formed with recessed portions into which said bolts project and by which the heads of the bolts are accommodated.

5. A roller mill including opposed heads, transversely extending bracket bars mounted upon the heads, arcuate circumferentially

extending liner bars carried by the bracket bars, shims spacing the liner bars between each pair of bracket bars from each other, means for adjusting the heads towards or from each other, and means for holding the 15 liner bars against the bracket bars.

In testimony whereof I hereunto affix my signature.

EDWARD FITZ-GERALD LAW.
